UNITED STATES PATENT OFFICE.

WILLIAM PINCIN, OF ALTOONA, PENNSYLVANIA.

ADJUSTABLE REAMER.

1,089,722.

Specification of Letters Patent. Patented Mar. 10, 1914.

Application filed December 15, 1911. Serial No. 665,942.

To all whom it may concern:

Be it known that I, WILLIAM PINCIN, a citizen of the United States, residing at Altoona, in the county of Blair and State 5 of Pennsylvania, have invented certain new and useful Improvements in Adjustable Reamers, of which the following is a specification.

This invention relates to machine tools 10 and specifically to reamers of the adjustable type, and the principal object of the same is to provide a new and practical method of adjustment for expansion reamers, whereby any desired diameter of hole 15 can be reamed absolutely true and accurate.

Another object of this invention is to provide improved means of holding the cutting edges, or blades, thus enabling the reamer to withstand rough usage, such as machine 20 tools are generally subjected to.

A further object of the invention is the micrometer adjustment together with the improved means to secure the adjustment.

With these and many other objects in 25 view, which will be more readily apparent, as the nature of the invention is better understood, the same consists of the novel construction, combination and arrangement of parts as will be hereinafter fully illustrated, 30 pointed out and claimed.

The essential features of the invention involved, in carrying out the objects above indicated, are naturally susceptible to a wide range of structural modification, within 35 the scope of the claim, but a preferred and practical embodiment thereof is shown in the accompanying drawings, in which:—

Figure 1 is a half sectional plan view of my improved expansion reamer, showing 40 all the parts assembled together, as the reamer would appear when ready for use. Fig. 2 is a side elevation of the parts shown in Fig. 1 of the drawings. Fig. 3 is an end elevation of the parts shown in Fig. 2. Fig. 45 4 is a side and edge elevation of the graduated adjusting nut. Fig. 5 is an edge and side view of the rear locking nut. Fig. 6 is a plan and side elevation of the cutting blade locking nut. This particular detail serves 50 to hold the rear end of the cutting blades in a firm position. Fig. 7 illustrates the side and end views of the adjusting mandrel. Fig. 8 is a plan and side elevation of the mandrel cap. Fig. 9 illustrates a front and 55 edge view of one of the adjusting nuts.

Fig. 10 shows an edge and side elevation of one of the cutting blades. Fig. 11 is a view of the locking pin.

Like reference numerals designate corresponding parts throughout the several figures of the drawings.

This improved adjustable reamer primarily consists of a body portion 10, having a shank 11, provided with a fluted portion 12, which is adapted to receive a projecting wing on the power head, thus enabling the reamer to rotate with the head. The body portion 10 is preferably threaded with a square thread as shown at 13, the threaded portion 13, receives the adjusting nuts 14, 15 and 16, and the cutting blade locking nut 17. The forward portion of the body 10 is provided with a plurality of grooves 18, into which are set the cutting elements 19. The lower curved surface 20, of the blade 19 75 abuts upon the concave surface 21, of the groove 18 in the body portion 10. This form of abutment provides a very practical means for minute adjustment of the blades which is a very necessary requirement for accurate 80 reaming.

The forward end portion 22, of the cutting blade 19, is provided with a locking ledge 23, which engages the beveled face 24 of the screw cap 25, which is preferably 85 provided with a plurality of diagonally opposite spaced drilled holes 26, which are intended to receive a wrench for adjusting the cap. The screw cap 25 serves in a very practical way to hold the sections "S", 90 firmly together through the action of the interlocking feature, as shown at 22^a, Fig. 1 of drawings. In addition to holding the segments firmly together, the cap 25, forms a seat which receives the forward end of the 95 cutting blades and firmly inter-locks them in position.

The inside face 27, of the cap 25, is engaged by the base 28 of the adjusting mandrel 29, the stem 30 of which occupies a 100 central position in the body 10. The hole in the body 10, which receives the stem 30 is preferably drilled, then reamed to size, while the hole in the forward end of the body 10, that receives the cone-shaped portion of the mandrel, may be cut out on a lathe before the grooves are cut, the finish of the inside surface not being essentially accurate, the only precautions necessary being to see that the inclined face of 105 110

the mandrel does not engage the inside face of the hole made in the body 10 for its reception.

The rear end of the cutting blade 19, is provided with a beveled face 32, which is engaged by the face 33, of the locking nut 17. By drawing the face 33 up against the inclined face 32 of the cutting blade, it is obvious that the blade will be forced up against the cap 25, and held in a firmly locked position. The blade locking nut 17 is provided with a hole 34, which is adapted to receive a wrench for adjusting purposes.

In addition to the locking nut 17, there is provided for adjusting purposes a graduated adjusting nut 16; the graduations on this nut being preferably made at $1/10$ inch apart, each graduation representing in this particular instrument $.025''$ of the cutting blades. The locking nut 16 is provided with a set screw 35, which is a necessary means of adjusting the position of the nut 16 to compensate for loss of size after grinding the blade 19. The locking nut 15 is also provided with a series of graduations 36, preferably 50 in number, when the taper of the portion 37 of the mandrel is 6 inches in 12 inches, which is preferred when a wide range of adjustment is required.

The adjustment of this improved reamer may be described as follows: To increase the size of the reamer, that is to set the blades out, thus enlarging the hole reamed: the locking nuts 14 and 17 are loosened, the

nut 14 is moved back, and the graduated nut 15 is revolved back likewise as many thousandths of an inch as desired. The screw cap 25 is then brought up against the base of the mandrel, thus forcing the blades out the desired amount. After the adjustment is complete, the locking nuts are again forced up thus making the adjustment complete.

Without further description and elaboration, it is thought that the many advantages of the herein described adjustable reamer are readily apparent.

What I claim is,

An adjustable reamer comprising a hollow cylindrical exteriorly threaded body, a stem provided with a cone shaped end portion adjustable in said body, a cap member associated with the cone shaped end of the said stem, cutting blades adapted to bear against the conical surface of the stem, a clamping nut adjustable on the exterior threaded portion of the body for clamping the blades upon the cone shaped end of the stem and also against the cap member, and graduated means for adjusting the blades also mounted on the exterior threaded portion of the body.

In testimony whereof I hereunto affix my signature in the presence of two witnesses.

WILLIAM PINCIN.
